GOLF PRACTICE DEVICE

Wesley A. Pottle, Denver, Colo.

Application May 24, 1932. Serial No. 613,177

7 Claims. (Cl. 273—35)

This invention relates to an amusement device which can also be used as a golf practice device if desired.

The principal object of the invention is to provide a mechanism which will be actuated by the flight of a first object, such as a golf ball, to propel a second object, such as an arrow, through the air.

Another object of the invention is to so construct the device that the direction of the propelled object will be controlled by the direction of flight of the first object so that its accuracy will depend upon the skill of the player.

The preferred embodiment of the invention comprises a device for projecting an arrow in accordance with the force and direction imparted to a golf ball through the use of regulation golf clubs. It is of course not limited to this particular embodiment but may be used to project any desired object in accordance with propelling force applied to a first object.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective illustration showing a permanent form of the invention in use.

Fig. 2 is a plan view of a portable form of the invention.

Fig. 3 is a section taken on the line 3—3, Fig. 2.

Fig. 4 is a side elevation of the form of Fig. 2 in place.

The preferred embodiment of the invention comprises a rotatable horizontal member 10 to which is secured a rearwardly extending flight board 11. Two levers, herein designated as "bow levers" 12, are pivoted at their forward extremities to the flight board 11 in spaced apart relation, so that they may be brought to a parallel position as shown in Fig. 2. The rearward or free extremities of the bow levers 12 are connected by means of a bow string 13.

The levers 12 are actuated by means of two flexible cords 14, there being one cord for each of the levers. The cords 14 extend forwardly from the levers through eye members 15 on the horizontal member 10, and thence rearwardly to a connection at 17 to a ball tether 18. The ball

tether 18 is permanently connected at its extremity in any desired manner to a suitable golf ball 19.

A coil tension spring 20 extends forwardly from each of the levers 12 to an attachment stud 21 on the flight board 11. The attachment studs 21 are positioned in parallel alignment with the pivot points of the levers 12 so that they will act to hold the levers in a parallel, dead-center position as shown in Fig. 2.

As thus far described the forms of Figs. 1 and 2 are similar. In the form of Fig. 1, however, the horizontal member 10 is journaled at 23 on a concrete wall 22 which surrounds an open pit of the proper shape to allow the device to operate.

In the form of Figs. 2 to 4, the horizontal member 10 is journaled at 24 to the extremities of a flat U-shaped, frame member 25. In installing the latter form, an open pit is dug having an outline and depth approximately as indicated by the broken line "A" in Figs. 2 and 3. The frame member 25 is then laid over the pit as illustrated and is held in place by means of spiked teeth 26 which project from the bottom of the frame member 25 for insertion in the ground.

In use the ball is teed up directly behind the device in the position shown in Fig. 2. An arrow 29 is then placed upon the flight board between the levers, as shown in Fig. 2, in engagement with the bow string 13. The user then by means of an ordinary golf club strikes the ball as though he were making the usual golf drive. The ball will start its flight and continue until it reaches the limit of the cords tether 18. The cords 14 will then act to jerk or swing the levers 12 outwardly, as shown in Fig. 1, so as to snap the bow string 13 tight and project the arrow into the air on a trajectory determined by the angle of the flight board 11.

It is desired to call particular attention to the action of the levers 12. It will be noted that as they swing away from each other the bow string will be progressively tightened at an increasingly rapid rate so as to provide a "follow-up" action on the arrow which will greatly assist in its projection. The arrow is continuously propelled from the position of Fig. 2 until the string reaches the position of Fig. 1. This action is similar to the usual action of a regulation bow.

The initial impulse of the cords 14 swings the levers 12 outwardly beyond their "dead-center" positions so that springs 20 are brought into action to overcome the initial inertia of the levers 12 and swing them outwardly. The springs are not intended to project the arrow. The latter

depends for its velocity upon the force imparted to the golf ball 19 by the driver. The horizontal member 10 may, if desired, be provided with a handle 27 by means of which it may be rotated 5 so as to change an angle of the flight board 11. The board can then be locked at any desired angle by means of a locking segment 28 so that the arrow will be projected on any desired trajectory.

It is desired to call particular attention to the 10 fact that the direction of the arrow's flight is controlled by the accuracy with which the golf ball is struck. For instance should the driver hook the ball so that its natural curve would be to the left the result would be that the right hand 15 cord 14 will tighten in advance of the left hand cord causing the right hand lever to be actuated ahead of the left hand lever. This causes the bow string 13 to swing the rear of the arrow to the right so that it will be projected to the left. 20 A sliced drive would have the opposite effect and project the arrow to the right. A straight, correct drive will tighten both cords 14 simultaneously and project the arrow straight ahead.

I claim:

25 1. An amusement device comprising: a flight board adapted to support an arrow; a ball; a flexible connection extending from said ball to said flight board and adapted to project said arrow from the latter when said ball reaches the extremity of said flexible connection.

30 2. An amusement device comprising: a flight board; a series of levers adapted to lie on, and hinged at their one extremities to, said flight board; a bow string connecting the other extremities of said levers and arranged to receive an arrow positioned upon said flight board; a ball; and a flexible connection between said ball and said levers so that the energy of said ball will be communicated to said levers when said 35 ball is struck to cause said bow string to project said arrow.

35 3. A device for projecting an arrow in consequence of the flight of a ball comprising: a flight member adapted to support said arrow; levers hinged at their one extremity to said flight member so that they may be brought in to parallel relation; a bow string connecting the free extremities of said levers and arranged to engage said arrow; a cord extending from each of said 45 levers to a common junction; and a tether between said ball and said junction so that the force of stopping the flight of said ball will be communicated to said levers to project said arrow.

40 4. A device for projecting an arrow in conse-

quence of the flight of a ball comprising: a flight board adapted to support said arrow; levers hinged at their one extremity to said flight board so that they may be brought in to parallel relation; a bow string connecting the free extremities of said levers and arranged to engage said arrow; a cord extending from each of said levers to a common junction; a tether between said ball and said junction so that the force of stopping the flight of said ball will be communicated to said levers to project said arrow; and cord guide members arranged to guide the angle of pull of said cords on said levers.

5. A device for projecting an arrow in consequence of the flight of a ball comprising: a flight member adapted to support said arrow; levers hinged at their one extremity to said flight member so that they may be brought in to parallel relation; a bow string connecting the free extremities of said levers and arranged to engage said arrow; a cord extending from each of said levers to a common junction; a tether between said ball and said junction so that the force of stopping the flight of said ball will be communicated to said levers to project said arrow; coil springs connected to said levers intermediate their extremities and each extending to a fixed attachment point; said attachment points being in alignment with the axis of said levers when the latter are in parallel position.

6. A device for projecting an arrow in consequence of the flight of a ball comprising: an inclined flight member adapted to support said arrow; levers hinged at their one extremity to said flight member so that they may be brought in to parallel relation; a bow string connecting the free extremities of said levers and arranged to engage said arrow; a cord extending from each of said levers to a common junction; and a tether between said ball and said junction so that the force of stopping the flight of said ball will be communicated to said levers to project said arrow; and means for varying the incline of said flight member.

7. An amusement device comprising: a projectile; a guide member arranged to initially guide said projectile; means for projecting said projectile into free flight in the air; said guide member directing the initial direction of said flight; a ball; an operative connection between said ball and said projecting means so that when said ball is struck, the energy imparted to said ball will be communicated to said projecting means to impel said projectile on its free flight.
